SPOON OR SIMILAR ARTICLE

Stephen P. Simon, Wallingford, Conn.

Application February 23, 1954, Serial No. 29,166

Term of patent 14 years

(Cl. D54—12)

To all whom it may concern:

Be it known that I, Stephen P. Simon, a citizen of the United States, residing in Wallingford, county of New Haven, and State of Connecticut, have invented a new, original, and ornamental Design for a Spoon or Similar Article, of which the following is a specification, reference being had to the accompanying drawing, forming part thereof, in which:

Fig. 1 is a front elevation of a spoon or similar article embodying my new design;

Fig. 2 is a side elevation of the same;

Fig. 3 is a section taken along the line 3—3 of Fig. 1, in the direction of the arrows; and

Fig. 4 is a section taken along the line 4—4 of Fig. 1, in the direction of the arrows.

I claim:

The ornamental design for a spoon or similar article, substantially as shown.
